UNITED STATES PATENT OFFICE.

JOHN CEDERSTROM, OF BUFFALO, NEW YORK, ASSIGNOR TO THE UNITED STATES AERATING FOUNTAIN COMPANY, OF SAME PLACE.

SIPHON-FILLING DEVICE.

SPECIFICATION forming part of Letters Patent No. 651,747, dated June 12, 1900.

Application filed February 9, 1900. Serial No. 4,630. (No model.)

To all whom it may concern:

Be it known that I, JOHN CEDERSTROM, of Buffalo, New York, have invented a new and useful Siphon-Filling Device, which is fully set forth in the following specification.

This invention is a device for filling siphons and the like with mineral waters or other liquids under high pressure. In general siphons are filled at bottling-works and then delivered to dealers. The present device can be applied to any bar or counter for the dealer to fill his own siphons, thus enabling him to give each customer a freshly-filled siphon. Besides by packing the main reservoir or the coil leading from it in ice the siphon receives its contents at a low temperature and is readily kept so, whereas if the siphons have to be delivered after filling at the bottling-works the temperature rises, which endangers the siphon and is objectionable.

When a liquid under high pressure is drawn from the main reservoir into a bottle or siphon, there is an almost inevitable leakage at the point of connection between the two, to say nothing of the danger of bursting the receptacle, and when the communication between the two is cut off and the siphon removed the gas and liquid remaining in the pipe and in the nozzle of the siphon "sniff" violently out and are liable to drench the attendant and splash the adjacent portion of the room. I avoid this by placing a sleeve or continuation upon the end of the connection from the reservoir. This continuation surrounds the joint between the siphon-nozzle and the reservoir connection to form a chamber that is completely closed by the insertion of the nozzle, except for an outlet or passage-way that carries off the leakage and that permits the gas remaining in the nozzle and in the communication when the controlling-valve is closed to sniff out harmlessly. My invention consists, further, in certain details of construction that will be more fully set forth.

In the drawing annexed hereto the figure shown is a vertical section of an embodiment of my invention.

A is the board or marble slab forming the bar or counter. The pipe B, leading from the coil or reservoir, is secured to the bar A

and carries the plug B'. On the plug is secured casting or head C, preferably at an angle, as shown. This head has an enlarged chamber at each end and a passage-way connecting them. A continuation of the walls of this passage-way at its inner end constitutes a flange c and provides the shoulder c'. Fitting within the passage-way is the tube D, provided near its outer end with the flange D', between which and shoulder c' is interposed a coiled spring c² to hold the tube normally retracted. On the inner end of the tube is screwed the cap E, whose annular flange e provides a seat for the washer or gasket e', that fits snugly around the tube. Radial openings d are provided near the inner end of the tube. When the tube is depressed, these openings d provide a continuous passage-way as an outlet from the reservoir; but when the spring retracts the tube washer e' is drawn closely against the flange c, openings d being covered, and the outlet is completely cut off. A second washer d³ is placed upon tube D, beyond flange D', fitting within the outer chamber of head C. A clamp or ring d' secures this second washer. A third gasket d" is placed on top of ring d' to form a seat for the end of the nozzle of a siphon. A sleeve F is screwed into the outer end of head C and upon the second washer d³, referred to. This sleeve has a flange f at its outer end to support annular gasket G, which is held in place by a centrally-apertured cap H, screwed upon the end of sleeve F. The opening in gasket G is barely large enough for the insertion of nozzle J of siphon K. An opening or passage-way I leads from this outer chamber of head C, preferably through a tube i, to the outer air.

The mode of operation is as follows: The nozzle J of a siphon is inserted into the opening of washer G and is pressed down until it surrounds the end of tube D, which latter is made of proper size to enter the nozzle readily. The nozzle is pressed still farther until its end rests closely upon the washer d", which produces a tight joint. Further pressure of the nozzle opens the valve, forcing tube D down against its spring until the openings d have cleared flange c. This permits the aerated liquid to pass freely from the reservoir

through plug B, openings d, tube D, and nozzle J into the siphon K. When the latter is sufficiently filled, it is withdrawn. The first result of withdrawing the nozzle is to release 5 the spring and close the valve. As the nozzle is farther withdrawn until it disengages tube D, but before it clears gasket G, the gas remaining within the tube and the nozzle passes into the outer chamber and is carried 10 off through passage-way I. Any leakage of the joints during the filling passes out readily through this opening.

I do not limit myself to the particular valve or the exact construction shown, for the spirit 15 of my invention consists in providing the closed chamber to snuff the leakage off harmlessly.

Having thus described my invention, I claim—

- 20 1. A siphon-filling device, the same comprising a head, a valve seated therein for controlling the outlet from the main reservoir and adapted to be opened by the application of the siphon-nozzle, a continuation of said head adapted to surround said nozzle to form a closed chamber about the same, and an aperture forming an outlet from said chamber, substantially as described.
- 25 2. A siphon-filling device, the same comprising a head, a spring-pressed tube seated in said head and forming part of the controlling-valve, said tube adapted to be encircled by the end of the siphon-nozzle, a flange near the end of said tube to receive the end of said 30 nozzle for depressing the tube to open the valve, a sleeve with an annular cap constituting a continuation of said head and forming (when said nozzle is inserted) a closed
- 35

chamber around the same, said sleeve being provided with an aperture to permit the discharge of gas from said chamber, substantially as described.

3. In combination with the head of a siphon-filling device, a sleeve or continuation thereon, an annular gasket carried in the end of 45 said sleeve to admit a siphon-nozzle, a spring-pressed tube in said head constituting a valve-controlled outlet, a flange on said tube to be engaged by said nozzle for opening said valve, said sleeve and gasket forming a closed chamber surrounding the end of the nozzle, and the said chamber being provided with an opening to carry off leakage, substantially as described.

4. The combination with the head of a siphon-filling device, and a spring-pressed tube seated therein and constituting a valve-controlled outlet and having near its end a washer, of a sleeve forming a continuation of said head and surrounding said tube to inclose a 50 chamber terminating in an annular gasket carried by said sleeve, and the nozzle of a siphon fitting snugly within said gasket to form a tight joint and encircling said tube to bear closely upon said washer and form a second 55 tight joint, said surrounding chamber being provided with an outlet for leakage, substantially as described.

In testimony whereof I have signed this specification in the presence of two subscribers. 60 70

JOHN CEDERSTROM.
